ROTARY SASH LOCK

Herman H. Kistner, Baltimore, Md.

Application June 23, 1938, Serial No. 215,483

8 Claims. (Cl. 70—90)

This invention relates to window sash locks of the type commonly used for double hung windows, having a catch fixed to the lower meeting rail of the upper sash adapted to be engaged by a spiral cam on a rotary thumb latch mounted to turn on the upper meeting rail of the lower sash to engage behind and under the catch to draw the two meeting rails together horizontally and prevent them from separating vertically, thereby maintaining a weather tight joint and preventing rattling of the sash.

The invention aims to provide a secure fastening and key operated locking means for such thumb operated locks for windows and other purposes, and comprises several varieties of locking mechanism as hereinafter described.

More specific objects of the invention are to prevent jimmeying or forcing double hung windows of the common type provided with a pivoted thumb latch engaging under a hook shape catch; to provide suitable deadlocking means for securing such window locks against opening from either within or without except by the use of a mating key; and to adapt the common type of multiple tumbler cylinder lock to deadlocking said window latch mechanism thereby producing an improved rotary type bolt lock.

With these objects in view the invention has been embodied in various designs, as illustrated in the accompanying drawings, wherein

Fig. 1 is a transverse cross-section through the meeting rails of a double hung window fitted with a thumb bolt having a wafer-type tumbler deadlocking mechanism;

Fig. 2 is a plan view of the same;

Fig. 3 is a vertical cross-section of the same at right angles to that of Fig. 1, said cross-sections being taken on the lines 3—3 and 4—4 in Fig. 2, respectively;

Figs. 4 and 5 are horizontal cross-sections of the same on the lines 4—4 and 5—5 in Fig. 3, respectively, Fig. 5 being drawn to a larger scale; and

Fig. 6 is a perspective view of the barrel which houses the deadlocking cylinder or plug and associated mechanism for controlling the movement of the rotary thumb bolt.

Figs. 7 to 12, inclusive, illustrate modifications of the invention, Figs. 7 and 8 being a vertical section (similar to Fig. 3) and cross-section thereof on the line 8—8 of a wafer type deadlocking mechanism which can be locked without a key, the plug in Fig. 8 being shown turned to the unlocked position; Figs. 9 and 10 being views similar to Figs. 1 and 3 of a pin tumbler type deadlocking mechanism; Fig. 11 being a bottom plan view of the upper rail illustrated in Fig. 9; and Fig. 12 being a view similar to Fig. 10 showing a pin tumbler type deadlocking mechanism

from which the key can be removed only in the locked position.

In the embodiment of the invention illustrated in Figs. 1 to 6, inclusive, the upper and lower meeting rails 11, 12 are shown in the closed position of the window sash, with the thumb latch or bolt 13 engaging its keeper 14 in locking position, and the wafer tumbler mechanism in deadlocking position, the key 15 being indicated in dotted lines in Fig. 1 as about to be inserted in the deadlocking plug 16. The thumb bolt 13 and hook shape keeper 14 are of the usual spiral cam type, so contrived as to pull the meeting rails together both laterally and vertically when the thumb bolt is forced as far as it will go in the clockwise or locking direction. The keeper is preferably secured to the upper surface of the upper sash meeting rail 11 by wood screws 17 in the usual manner and also by a through stud or screw 18 which is inserted from below and engages a threaded hole in a boss 19 projecting from the under face of the keeper 14 into a socket in the rail 11. The lower end of the stud carries a flanged washer or circular nut 20 which is let into a counterbored recess in the under face of the rail 11, and after being screwed home, the head of the stud is cut off and riveted over the outer face of the washer to prevent withdrawal.

The body 21 of the thumb bolt assembly is secured to the upper face of the meeting rail 12 of the lower sash by means of screws 22, and is provided with a central barrel 23 let into a hole bored for it in the meeting rail which helps to secure it in place. This barrel may be integral with the body (as shown in Fig. 7) or it may be a separate part secured to the body by screws 24, engaging in lugs 25 one on each side of the barrel, that fit in recesses 26 formed on the under side of the body, as shown in Figs. 3, 4 and 6. The upper end of the barrel 23 is preferably counterbored to receive a flange or collar 27 on the under side of the thumb bolt which fits with in a central hole in the body 21 and serves to position and guide the thumb bolt. A flange 28 on the upper end of the plug 16 retains the thumb bolt in place. The cylinder 16 is provided with opposite lugs 29 which engage in recesses 30 at opposite sides of the central hole in the thumb bolt to permit the latter to turn through a small angle in either direction with respect to the plug when the latter is in deadlocking position, thereby permitting the thumb bolt to be turned independently of the deadlocking means sufficiently to clamp the meeting rails securely together to prevent draftiness and rattling.

The barrel 23 has slots or grooves 31 on opposite sides to receive the ends of the sliding tumblers 32 of usual form carried by the locking plug in transverse slots shaped to receive them.

These tumblers are pressed out from their respective slots into engagement with the grooves 31 by means of springs 33 also mounted in recesses in the plug, except when withdrawn by the proper key which passes through and engages in openings 34 therein. The locking plug turns freely in the barrel and is retained therein by means of a collar or washer 35 secured on its reduced lower end by a screw 36 or other suitable means. A spring 37 is compressed between the washer and an internal flange or ledge 38 in the barrel to hold the plug 16 in place and prevent the thumb bolt 14 from rattling or turning too easily.

In the form of the invention illustrated in Figs. 1 to 6, inclusive, the key must be inserted in the deadlocking plug in order to turn the plug from either its deadlocked or its unlocked position, as the ends of the tumblers normally engage in one or the other of the grooves 31 and securely hold the plug against rotation. But in the form of the invention illustrated in Figs. 7 and 8, one of the side walls of the groove 31 in the barrel portion of the body 39 which receives the ends of the tumblers 32 in unlocked position is beveled off to form a sloping face 40 along which the tumblers may slide inwards when the plug is turned from unlocked position, as may be done by turning the thumb bolt towards the locking position without using the key.

The modification of the invention illustrated in Figs. 9, 10 and 11 comprises a thumb bolt 41 and keeper 42 having a spiral cam action similar to the common type of window lock, and provided with a deadlocking mechanism consisting of a cylinder 43 mounted to turn in the body 44 and upon which the thumb bolt is secured by means permitting a limited angular movement, as in the form of the invention illustrated in Figs. 1, 2 and 3. In the form shown in Figs. 9 and 10, the lock is deadlocked by pin tumbler locking devices mounted in the cylinder and body, there being two sets of alining tumblers 45 oppositely disposed in transverse rows or banks of holes in the body and pressed towards the cylinder by springs 46 in the holes, and a single set of driving pins 47 mounted in a row or bank of holes in the cylinder and adapted to aline with one or the other bank of tumblers depending on whether the cylinder is in deadlocked or unlocked position. The cylinder is retained in the body 44 by means of a collar 48 secured on its inner end by a screw 49, or other suitable means, and against which a spring 50 bears at one end, the other end of the spring resting against an internal flange or abutment 51 in the body, as shown. The spring presses the cylinder and thumb bolt downwardly against the upper face of the body 44, which has an ornamental base or casing 52 through which pass screws or other means 53 for securing it to the meeting rail 54 of the lower sash.

The keeper 42 is preferably secured to the meeting rail of the upper sash 55 by two screws or bolts 56 which pass upwardly through the meeting rail and engage in spaced lugs 57 on the under side of the body of the keeper, their lower ends being flush with the lower face of the bearing plate 58 set into a suitable recess in the under side of the meeting rail. Preferably the heads 59 of the bolts are provided with one way screw driver slots permitting them to be firmly screwed into place but preventing their removal. If desired, the heads of the securing bolts or screws may be cut off or filed smooth

in order to prevent withdrawal after they have been screwed home. This mode of attachment of the keeper to the meeting rail provides a secure fastening which cannot be readily undone by use of the usual tools possessed by sneak thieves and housebreakers.

The modified form of pin tumbler deadlocking means illustrated in Fig. 12 is similar to that shown in Figs. 9 and 10, excepting that there is only one bank of tumblers 45 for holding the cylinder 43 against rotation, this bank being so placed as to hold the cylinder in its deadlocking position. The key may be inserted in the cylinder and removed therefrom in the deadlocking position, but in all other positions of the cylinder 43, the driving pins 47 will engage the bore of the body portion 60 of the lock structure and thereby prevent the key from being removed from the lock while permitting the cylinder to be turned in either direction.

In all three forms illustrated, the latch member assembly comprises a unitary assemblage of supporting body, rotatable thumb bolt for engaging the keeper, and dead-locking cylinder rotatably mounted in a recess in the body for coaxial movement with said thumb bolt, thereby providing a simple, readily applied lock for double hung windows.

The invention provides a strong, compact form of lock which cannot be removed from the sash when deadlocked in locking position, and which furnishes a secure means for keeping the window to which it is applied closed against efforts to open it from either without or within in the absence of the mating key. As many different key combinations as desired can be used for different locks or groups of locks. For example, all the windows in one room or part of the house may be provided with locks fitted for the same key combination, which can be changed as often as may be desired.

The invention may be readily adapted to various purposes for which rotatable latches having deadlocking means are desirable, and it is not restricted to the details of construction exactly as illustrated herein.

What I claim is as follows:

1. A lock member assembly for a rotary thumb latch type lock of the character described, said lock member assembly comprising a body, a thumb bolt mounted for rotation on said body, a dead-locking cylinder mounted for rotation in said body coaxially with said thumb bolt and having an axial key receiving slot, key actuated members transversely disposed in said cylinder intersecting said slot, and means cooperating therewith for holding said cylinder against rotation except when the proper key is inserted in said slot, and an operative connection between said thumb bolt and cylinder.

2. A lock member assembly for a rotary thumb latch type lock of the character described, said lock member assembly comprising a body, a thumb bolt mounted for rotation on said body, a dead-locking cylinder mounted for rotation in said body coaxially with said thumb bolt and having an axial key receiving slot, key actuated members transversely disposed in said cylinder intersecting said slot, and means cooperating therewith for holding said cylinder against rotation except when the proper key is inserted in said slot, an operative connection between said thumb bolt and cylinder providing limited freedom for angular movement of one with respect

to the other, and manual means for rotating said thumb bolt.

3. In a bolt lock having a rotary locking member assembly and a fixed keeper member adapted to be respectively applied to two relatively movable portions of a structure, the combination of a bolt mounted in said locking member assembly for rotation about a fixed axis, and a cylinder rotatably mounted in a coaxial recess in said assembly and provided with a bolt engaging element, said cylinder having an axial slot to receive a key, transverse slots in said cylinder intersecting said axial slot and key engaging slides carried thereby, said assembly having the side wall of said cylinder receiving recess shaped to receive the outer ends of said slides to allow them to project from said slots in deadlocking position thereby permitting insertion of the key, means cooperating with said slides to prevent rotation of said cylinder from deadlocking position except when the proper key is in said axial slot in engagement therewith, means for rotating said bolt and cylinder, and means on said keeper member with which said bolt engages in deadlocking position of said cylinder to prevent separation of said locking member assembly and keeper member both axially and transversely of the axis of said cylinder.

4. In a bolt lock having a rotary locking member assembly and a fixed keeper member adapted to be respectively applied to two relatively movable portions of a structure, the combination of a bolt mounted in said locking member assembly for rotation about a fixed axis, and a cylinder rotatably mounted in a coaxial recess in said assembly and having bolt engaging means on its exposed end for permitting limited angular movement of said bolt with respect thereto, said cylinder having an axial slot to receive a key, transverse slots in said cylinder and key engaging slides carried thereby, said assembly having the side wall of said cylinder receiving recess shaped to receive the outer ends of said slides to allow them to project from said slots in deadlocking position thereby permitting insertion of the key, means cooperating with said slides to prevent rotation of said cylinder from deadlocking position except when the proper key is in said axial slot in engagement therewith, means for rotating said bolt independently of said cylinder, and means on said keeper member with which said bolt engages in deadlocking position of said cylinder to prevent separation of said locking member assembly and keeper member both axially and transversely of the axis of said cylinder, said bolt and keeper member being adjustable to maintain a tight fit within the capacity for angular movement between said bolt and cylinder.

5. In a locking means for double hung windows including a keeper secured to one sash meeting rail and a rotary thumb bolt mounted on a body secured to the other sash meeting rail, said rotary thumb bolt having a spiral cam for engaging said keeper to draw said sash meeting rails together vertically and transversely to close the gap between them and prevent rattling, the combination of a cylinder rotatable in said body with its axis coaxial with the axis of rotation of said rotary thumb bolt, said cylinder having one end exposed adjacent to said thumb bolt, a driving connection between said cylinder and thumb bolt, an axial key slot in said cylinder opening

through said exposed end, said body having means for preventing rotation of said cylinder, and slides carried by said cylinder adapted to cooperate with said means for preventing rotation of said cylinder in the absence of the mating key.

6. In a locking means for double hung windows including a keeper secured to one sash meeting rail and a rotary thumb bolt mounted on a body secured to the other sash meeting rail, said rotary thumb bolt having a spiral cam for engaging said keeper to draw meeting rails together vertically and transversely to close the gap between them and prevent rattling, the combination of a cylinder disposed in said body with its axis coaxial with the axis of rotation of said rotary thumb bolt, said cylinder having one end exposed adjacent to said thumb bolt, a driving connection between said cylinder and thumb bolt, an axial key slot in said cylinder opening through said exposed end, said body having means for preventing rotation of said cylinder, and slides carried by said cylinder intersecting said slot and adapted to cooperate with said means carried by said body for deadlocking and unlocking said cylinder, said driving connection between said cylinder and thumb bolt permitting limited movement of the latter with respect to the cylinder when the latter is in deadlocking position.

7. In a rotary bolt and keeper type of sash lock, a body member adapted to be secured to a sash member, a bolt member supported by said body, said body having a cylindrical recess provided with an internal ledge near its bottom, a cylindrical rotatably mounted in said recess provided with key responsive means cooperating with said body for deadlocking said bolt member, said cylinder having an operative connection with said bolt member at its outer end and a projection at its inner end extending through said internal ledge and provided with an abutment, and a compression spring surrounding the inner end of said cylinder and bearing against said internal ledge and abutment to press said cylinder towards the inner end of said recess, whereby said cylinder and bolt member are retained in frictional contact with said body member permitting rotation of said cylinder and bolt member when said deadlocking means are released by the proper key.

8. In a sash lock, a body member adapted to be secured to a sash member, a bolt member supported by said body, said body having a cylindrical recess provided with an internal ledge near its bottom, a cylinder rotatably mounted in said recess operatively connected with said bolt member and provided with key responsive means cooperating with said body for deadlocking said bolt member, said cylinder having a flange overlying said bolt member at its outer end and a projection at its inner end extending through said internal ledge and provided with a removable cap, and a compression spring surrounding the inner end of said cylinder and bearing against said internal ledge and cap to press said cylinder towards the inner end of said recess, whereby said cylinder and bolt member are retained in frictional contact with said body member permitting rotation of said cylinder and bolt member when said deadlocking means are released by the proper key.
